UNITED STATES PATENT OFFICE.

ARTHUR TEICHLER, OF CHICAGO, ILLINOIS.

SLED.

1,134,973.

Specification of Letters Patent. Patented Jan. 12, 1915.

Application filed May 3, 1913. Serial No. 765,301.

To all whom it may concern:

Be it known that I, ARTHUR TEICHLER, a citizen of the United States, residing at Chicago, in the county of Cook and State of Illinois, have invented new and useful Improvements in Sleds, of which the following is a specification.

The invention provides a vehicle which in its specific foundation is mounted upon runners and is adapted to be propelled by the foot of the rider, the latter occupying a standing position and utilizing one of the feet as propelling means.

The invention consists essentially of the novel framework and the steering means, said framework being preferably of metal and the runners being arranged to adapt themselves to irregularities in the surface and the front or steering runner being mounted to turn freely about a vertical axis and controlled by means of a handle bar through a steering post.

The invention consists of the novel features, details of construction and combination of parts, which hereinafter will be more particularly set forth, illustrated in the accompanying drawings, and pointed out in the appended claim.

Referring to the drawings, forming a part of the specification, Figure 1 is a perspective view of a sled embodying the invention. Fig. 2 is a top plan view. Fig. 3 is a vertical central longitudinal section. Fig. 4 is a front view. Fig. 5 is a top plan view of a portion of the sled showing the parts on a larger scale and having the platform omitted. Fig. 6 is a detail perspective view of the several members comprising the frame work, such members being separated and arranged in a group.

Corresponding and like parts are referred to in the following description, and indicated in all the views of the drawings, by the same reference characters.

The sled embodies a front runner 1 and rear runners 2, the front runner being mounted to turn about a vertical axis to admit of the sled being properly started. The runners are preferably of similar or like formation, the body portion being preferably of wood which is provided upon its under side with wear irons. The runners are pivotally supported intermediate of their ends to admit of a free movement whereby the runners may adapt themselves to irregulari-

ties in the surface so as to engage with such surface throughout their length.

The framework of the sled is preferably constructed of metal and receives a platform 3 of wood which may be secured thereto in any way. The frame embodies longitudinal bars 4 and a plurality of transverse bars 5 which have their end portions bent downwardly and riveted or otherwise secured to the longitudinal bars 4. The longitudinal bars 4 converge forwardly and the transverse bars 5 correspondingly vary in length according to their relative position. Plates 6 are secured to the forward ends of the longitudinal bars 4 and other bars 7 connect the plates 6 with the forward transverse bar 5. Each of the plates 6 and bars 7 are of integral formation and have a right angle arrangement, the front cross bar being fastened to both bars 7 and 4. A cross piece 8 is secured to the front end of the platform 3 and projects above the same slightly to engage the foot and prevent the same from slipping over the front end of the platform when the sled is in motion. A V shaped iron 9 is secured to the front ends of the plates 6 and supports a fork 10, the stem of which is journaled in the iron 9 so as to turn about a vertical axis. The fork 10 embraces the front or steering runner 1 and is pivotally connected thereto by means of a bolt or like fastening 11. A second fork 12 is connected to the fork 10 and runner 1 by the same bolt or fastening 11 and receives a steering post 13, which extends vertically and is provided at its upper end with a handle bar 14. Blocks 15 are secured to the rear portion of the framework and the rear runners 2 are pivotally connected thereto by means of bolts or analogous fastenings 16.

When the sled is in motion it may be steered by means of the runner 1 through the handle bar 14, steering post 13 and connecting forks 10 and 12. The sled is particularly designed to be propelled by a pushing action which is effected by means of the rider who stands upon the platform upon one foot and utilizes the other foot as propelling means, such foot being intermittently brought in contact with the surface and utilized to impart an impelling force to the sled for driving the same. When coasting or when the sled is running freely the rider may stand upon the plat-

form with both feet in contact therewith. It is to be understood that the sled may be drawn, a rope or cord being connected thereto in any manner, as will be readily understood and for this purpose the cross piece 8 is shown as provided with eyes 17.

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claim appended hereto.

Having thus described the invention what is claimed as new, is:—

In a vehicle of the character specified, a

frame work embodying longitudinal and transverse bars, the longitudinal bars being 25 forwardly converged, plates secured to the front ends of the longitudinal bars, other bars formed with the plates and arranged at a right angle thereto and secured to the front transverse bar, a V-shaped iron connected with the said plates, a fork having its stem journaled in the V-shaped iron, a vehicle support arranged between the fork members, a second fork having its members embracing the V-shaped iron and the members 35 of the first mentioned fork and a fastening connecting the members of the fork to one another and forming connecting means between the vehicle support and the first mentioned fork.

In testimony whereof I affix my signature in presence of two witnesses.

ARTHUR TEICHLER
